UNITED STATES PATENT OFFICE.

GEORGE LITTLE, OF DENVER, COLORADO.

DESIGN FOR A WORK-TABLE.

No. 38,149.

Specification for Design.

Patented July 31, 1906.

Application filed May 18, 1906. Serial No. 317,629. Term of patent 7 years.

To all whom it may concern:

Be it known that I, GEORGE LITTLE, a citizen of the United States, residing in the city and county of Denver and State of Colorado, have invented a new, original, and ornamental Design for a Work-Table, reference being had to the accompanying drawings, which form a part of this specification.

This invention relates to a new, original, and ornamental design for a work-table, the said design being illustrated in the accompanying drawings, in which—

Figure 1 is a side elevation, and Fig. 2 a top plan view, of a table, showing my new design.

I claim—

The ornamental design for a work-table as shown.

GEORGE LITTLE.
